UNITED STATES PATENT OFFICE.

JONATHAN LEE, OF OTTUMWA, IOWA.

DESIGN FOR A BURIAL-COUCH.

45,564.

Specification for Design.

Patented Apr. 7, 1914.

Application filed February 9, 1914. Serial No. 817,707. Term of patent 14 years.

To all whom it may concern:

Be it known that I, JONATHAN LEE, a citizen of the United States, residing at Ottumwa, in the county of Wapello and State of Iowa, have invented a new, original, and ornamental Design for a Burial-Couch, of which the following is a specification, reference being had therein to the accompanying drawing, forming part thereof.

Figure 1 is a perspective view of one side of the burial couch showing my new design. Fig. 2 is a perspective view of the opposite side of the burial couch showing my new design.

I claim:

The ornamental design for a burial couch, as shown.

In testimony whereof I hereunto affix my signature in presence of two witnesses.

JONATHAN LEE.

Witnesses:

E. M. BROOKS,
R. H. LOREN ALLEN.
